19,013

VALVE-SEAT FINISHING TOOL

Edward E. Neldner, Milwaukee, Wis.

Original No. 1,789,080, dated January 13, 1931,
 Serial No. 209,416, July 30, 1927. Application
 for reissue January 12, 1933. Serial No.
 651,428

6 Claims. (Cl. 90—12.5)

This invention relates to tools for finishing the seats of poppet valves.

One object of the present invention is the provision of a tool of simple and economical design capable of finishing or refinishing poppet valve seats with utmost accuracy.

Another object is the provision of a tool for the purposes named which may be expeditiously applied, accurately centered, and firmly anchored 10 in the work with a minimum effort on the part of the operator.

Another object is the provision of new and improved centering means for a tool of the character mentioned.

15 Other objects and advantages will appear from the following description of an illustrative embodiment of the present invention.

In the drawing:—

Figure 1 is a view half in section and half in 20 elevation of a tool constructed in accordance with the present invention, illustrating the mode of applying the same to a valve seat of conventional form.

Fig. 2 is a view in elevation of a modified form 25 of tool centering means.

The tool selected for illustration comprises a guide spindle 10 designed for insertion within the usual valve-stem guide 11 and constituting a support and guide for a milling cutter 12, of a well 30 known type. The cutter shown is of a type commonly used in the refinishing of valve seats. In this instance the cutter 12 is firmly anchored upon the tapered end 13 of a sleeve 14 of moderate length, closely fitted for rotation and lengthwise travel upon the spindle 10. Appropriate means such as a nut 15 on the sleeve 14 retains the cutter in proper position thereon. A jam nut 16, threaded on the sleeve 14 immediately above the cutter 12, serves as a convenient means for 40 forcing the cutter from its normally tight fit upon the tapered end 13 and thus facilitates removal of the cutter when occasion arises.

The sleeve 14 also carries a ratchet wheel 17, which in this instance is formed integral therewith, and which coacts with a spring loaded pawl 18 in an appropriate handle 19 to effect rotation of the sleeve 14 and cutter 12 upon the spindle. The handle shown projects from a head 20 rotatably mounted upon the sleeve 14 and confined 50 beneath a collar 21 removably fixed to the upper end of the sleeve by suitable means such as a set screw 22. The sleeve 14, carrying the cutter 12 and handle 19, is thus free to rotate upon and travel along the spindle 10, and the relatively long bearing surface between the sleeve and spin-

dle insures absolute coincidence between the axes of the cutter and spindle.

Provision is also made in the tool shown for imparting a positive feed motion to the cutter along the spindle toward the work. This is accomplished in this instance by the use of a screw 23 mounted upon the upper portion of the spindle 10 and adjustably fixed thereto by a set screw 24. The screw shown is provided with a head 25 by which the spindle may be conveniently rotated for a purpose which will hereinafter appear. An elongated feed nut 26, threaded upon the screw 24, is disposed to bear at its lower end upon the collar 21, so as to force the collar 21, sleeve 14, and cutter 12 downwardly along the spindle 10 when the nut is rotated in one direction upon the screw 25. When rotated in the other direction the nut recedes from the collar 21 thereby permitting an elevation of the sleeve and cutter along the spindle.

In the tool shown the spindle is provided with a pair of longitudinally spaced centering elements designed to coact with the valve-stem guide 11 to effect and maintain coincidence of the axes of the guide and spindle, and to securely clamp the spindle to the work. One of the elements shown is in the form of a cone shaped member 27 disposed coaxially of and upon the spindle and having a tapered end 28 adapted to seat within the upper end of the guide 11. In this instance the member 27 is formed as an integral part of the spindle. The other element shown is in the form of a sleeve 29 disposed coaxially of the spindle and slotted for a portion of its length so that one end 30 thereof is expandable. The wall of the expandable end 30 is internally tapered, as at 31, for coaction with a similarly tapered shoulder 32 on the spindle. The other or solid end 33 of the sleeve is threaded upon the end 34 of the spindle. The diameter of the sleeve 29 is somewhat less than that of the guide 11 so that it may be passed freely, with the spindle, into the guide. The arrangement is such that relative rotation between the spindle and sleeve in such direction as to force the tapered end 31 thereof against the shoulder 32 will result in spreading the expandable end 30 of the sleeve against the internal wall of the guide and thus accurately center and firmly anchor the spindle therein.

The tool is ordinarily applied and operated as follows. Assuming that the nut 26 is retracted so as to permit free travel of the cutter 12 along the spindle 10, the lower end of the spindle, carrying the sleeve 29, is lowered into the valve-stem guide 11 until the tapered end 28 of the member 110

- 27 is firmly seated in the upper open end of the guide 11. Before entering the sleeve 29 into the guide, however, the expansible end thereof is preferably somewhat expanded by the shoulder 5 32 on the spindle so as to make light contact with the internal surface of the guide as it passes downwardly therein. After the member 27 is thus firmly seated the spindle 10 is rotated by manipulation of the head 25 on the fixed screw 10 24, or otherwise, in such direction as to force the sleeve 29 upwardly and thus expand the same forcibly against the internal surface of the guide 11. This action is made possible by reason of the fact that the sleeve 29 is retained against rotation 15 by the initial contact thereof with the guide. The member 27 and sleeve 29 thus provide a two point centering means for the spindle. In this position of the spindle the cutter 12 rests by gravity upon the unfinished valve seat conventionally shown at 35 and is accurately centered by reason 20 of this concentric mounting on the spindle. The feed nut 26 is then advanced against the collar 21 to establish the required pressure between the cutter and work and while this pressure is maintained the cutter is rotated until the desired 25 finish upon the work is obtained. Thereafter the tool may be readily released from the work merely by rotation of the spindle in such direction as to release the sleeve 29.
- 30 It will be noted that the cone member 27 is of such dimensions as to coat successfully with valve-stem guides of various diameters, and although the expansibility of the sleeve 29 will permit of some variation in guide sizes, the range 35 of permissible variations may be extended by the use of sleeves of various sizes. It will also be noted that adjustability of the screw 24 upon the spindle 10 together with the adjustability of the feed nut 26 upon the screw affords a wide 40 range of adjustment of the cutter 12 upon the spindle 10, so that the tool can be readily accommodated to various classes of work involving a wide variation in the distance between the valve seat and the top of the valve-stem guide.
- 45 A modified form of spindle centering element is shown in Figure 2, which in some instances may be advantageously substituted for the sleeve 29 of Figure 1. This element comprises a cone member 36 threaded upon the lower end 34' of 50 the spindle 10' and having a tapered end 37 adapted to seat within the lower end of a valve-stem guide 11'. When such an element is used it is applied to the spindle 10' after the spindle has been projected through the guide. It serves 55 to center the lower end of the spindle and coacts with the other cone member to securely anchor the spindle against end play.
- Various changes may be made in the tool hereinabove specifically described without departing 60 from or sacrificing the advantages of the invention as defined in the appended claims.
- I claim:
1. In a valve-seat finishing tool the combination of a spindle for insertion within a valve-stem guide, expansible means movably mounted concentrically of said spindle, means responsive to relative movement between said spindle and expansible means for expanding said means against the internal surface of the guide to center the spindle therein, a tapered element disposed con-
- centrically of said spindle for engagement within said guide and cooperating with said expansible means to effect accurate alignment of said spindle within the guide, and a rotary valve-seat finishing element centered by said spindle, said element being slidably mounted on said spindle and having a valve-seat engaging portion axially spaced from said tapered element. 80
2. In a valve-seat finishing tool the combination of a spindle for insertion within a valve-stem guide, a sleeve threaded on said spindle, said sleeve having an integral expansible portion, means on said spindle operable to expand said sleeve by relative rotation between said spindle and sleeve, and a valve-seat finishing element rotatably mounted upon said spindle above said sleeve. 85
3. In a valve-seat finishing tool the combination of a spindle for insertion within a valve-stem guide, a sleeve on said spindle and having a portion expansible against said guide, means on said spindle coacting with said portion to expand the same by relative rotation of said spindle in said guide, a tapered element on said spindle co-operating with said portion to accurately align 90 said spindle within the guide, and a valve-seat finishing tool rotatably mounted on said spindle. 95
4. In a valve seating tool, a post having a reduced portion at one end, part of said portion being tapered and the end threaded, a sleeve 105 having a bore with a screw threaded section engaging the threaded portion of the post and a tapered section corresponding to the taper of the post, said sleeve being slotted from the tapered end toward the threaded end, a second sleeve 110 fitted on the opposite end of said post, and a valve seat cutter attached to said sleeve and rotatable therewith on the post. 100
5. In a valve-seat finishing tool the combination of expansible means for engagement within 115 a valve-stem guide, a spindle for insertion within the guide and rotatable with respect to said expansible means, means responsive to rotation of said spindle within the guide for expanding said first named means against the walls of the guide, 120 a concentric tapered element on said spindle for engagement within said guide and for cooperation with said expansible means to effect accurate alignment of said spindle within the guide, and a valve-seat finishing tool rotatable on and 125 centered by said spindle, said tool being slidably mounted on said spindle and having a valve-seat engaging portion normally offset axially from said tapered element. 130
6. In a valve seat finishing tool, the combination of a spindle having an expansible centering means rotatable thereon and insertable therewith into a valve stem guide, means responsive to rotation of said spindle for expanding said centering means against the internal surface of 135 the guide, a second centering means on said spindle for coaction with the guide and co-operable with said first named centering means to align said spindle with said guide, and a valve seat finishing tool rotatable on and centered by 140 said spindle, said tool having a valve seat engaging portion normally offset axially from said second centering means. 145
